Tora Coleman, New York, N. Y.

Application March 11, 1938, Serial No. 75,748

Term of patent 3½ years

To all whom it may concern:

Be it known that I, Tora Coleman, a citizen of Latvia, residing in New York city, in the Borough of Manhattan, county and State of New York, have invented a new, original, and ornamental Design for a Dress Ensemble, of which the following is a specification, reference being had to the accompanying drawing, forming part thereof, wherein,

Figure 1 is a front view of a dress ensemble showing my new design.

Figure 2 is a front view of the dress unit of the dress ensemble shown in Figure 1.

Figure 3 is a rear view of the dress unit shown in Figure 2.

Figure 4 is a rear view of the jacket unit of the dress ensemble shown in Figure 1.

The characteristic feature of my design resides in the combination of the specific jacket member with the instant dress, which features a pin tucked skirt, a cummerbund sash and a print blouse, as shown.

I claim:

The ornamental design for a dress ensemble, substantially as shown and described.

TORA COLEMAN.
